UNIVERSAL CABLE-CLAMPING DEVICE

Leo L. Verkuil, Tottenville, Staten Island, N. Y., assignor to Edwards and Company, Inc., Norwalk, Conn., a corporation of New York

Application July 26, 1946, Serial No. 686,480

11 Claims. (Cl. 24—81)

1.

This invention relates to a device for clamping or securing or attaching a flexible or electrical conductor or cable, such as the cable to the end of which is connected a signalling switch to be actuated by a hospital bed patient, to the bed clothes, or to a fixed part such as a post or rail of the bed or like structure.

One of the objects of this invention is to provide a simple, reliable and convenient device that will be capable of easy manual manipulation and of wide flexibility, adaptation, particularly for anchoring or securing a portion of the cable of the above mentioned type so as to maintain the signalling switch within easy reach of the patient. Another object is to provide a device of this character that will dependably avoid having to use pins, or safety pins for attaching such a cable to the bed sheets, or bed clothes, it being well known that the use of such pins causes substantial damage to the bed clothes and particularly to the sheetings and also entails a risk of damaging the cable itself. Another object is to provide a device of the above mentioned character which will be readily detachable to or detachable from, as well as, shiftable relative to, the cable or flexible conductor and thus provide wide adaptability of application, and, at the same time, provide for the ready attachment of the cable or any selected portion of it, to the desired object or other temporary anchorage. Another object is to provide a cable attachment which will be capable of ready and convenient attachment to the end portions, or two sides of a loop of the cable, so that any selected portion of the cable may be looped about a part such as a bed post, and by the loop hold the cable and related devices in the desired positions. Another object is to provide a strong, compact and durable clamping device that will be well adapted to attachment by clamping action. Another object is to provide a clamping device that will have the advantages of a multiple clamping action and thus be capable, for example, of clamping one part such as a cable and of attachment by clamping action to another part such as a cable, a bed sheet or blanket or some other part which may be rigid or not. Another object is to provide a device of the above mentioned character that will be dependable and of inexpensive construction, and reliable action under varying conditions of practical use, and of simplicity and facility of manual manipulation or application.

The invention accordingly consists in the features of construction, combinations of elements, and arrangements of parts as will be exemplified

2.

in the structure to be hereinafter described and the scope of the application of which will be indicated in the following claims.

In the accompanying drawing in which is shown by way of illustration one of the various possible embodiments of this invention,

Fig. 1 is a top plan view or elevation of the clamping device;

Fig. 2 is a front elevation thereof;

Fig. 3 is a bottom view as seen from the bottom of Fig. 2;

Fig. 4 is a longitudinal vertical sectional view as seen, along the line 4—4 of Figs. 1 and 3;

Fig. 5 is a transverse sectional view as seen along the line 5—5 of Fig. 2;

Fig. 6 is a side elevation of one of the parts before assembly;

Fig. 7 is a diagrammatic view illustrating one possible mode of application of the device, and

Fig. 8 is a similar diagrammatic view showing another possible mode of application.

Similar reference characters refer to similar parts throughout the several views of the drawing.

I first provide a casing or housing 10 which may be made of any suitable material, preferably non-metallic, and conveniently of any suitable moldable material like any of the well known molding resins; the housing 10 is shaped to provide a top wall 11 with depending side walls 12, 13, and end walls 14, 15, the housing thus being open at the bottom. In the lower ends of the walls 14, 15, are openings or slots 16, 17, respectively, opening into the bottom edges of these side walls and being of ample size to accommodate therewith the flexible, insulated cable structure with which the device is to coact. With the slots 16, 17, thus open-ended, a run of the cable is readily and easily entered into the slots and is thus made to longitudinally traverse the interior of the housing 10, and need not be threaded through any holes or openings.

The top wall 11 is provided with two openings 18 and 19 which may be of rectangular shape to movably accommodate therein the lever arm extensions 20 and 21, respectively, of two preferable identical sheet metal levers which in Fig. 5 are generally indicated by the reference characters 22 and 23, the arms 20 and 21 being upward extensions of plate-like clamping jaw elements 24 and 25 respectively. In Fig. 6 one of these lever clamping members 22 is shown as it would appear when seen from the left in Fig. 5 and it will be seen to be shaped in a manner to facilitate punching and stamping thereof out of the suit-

able heavy sheet metal, the plate portion 24 being of a width approximating the length of the interior of the housing with the lever arm 20 thereof extending centrally and upwardly therefrom; to either side of the arm 20 the plate portion 24 has L-shaped extensions 27, 28 (see also Fig. 5), the faces of the vertical portions of which are preferably depressed or recessed as at 29 and 30, respectively, to form trunnions or partial bearing recesses for coaction with a pivoting pin later described. The lower end of the plate portion 24 is curved and may be serrated at its edge as indicated at 31 (see Fig. 3) to form a gripping jaw.

To the under face of the top wall 11 is secured as by screws 33 which pass through extension ears 34, a slit tube-like member 35 made of a suitable spring sheet metal preferably steel, the ears 34 being integrally formed therewith. As is better seen in Fig. 5, the two clamping levers 22, 23, with the arms 20 and 21 thereof extending upwardly through the holes 18 and 19 in the top wall 11, as the vertical arms of their L-shaped extensions 27 and 28 extended into the interior of the slit spring tube element 35 which is strained open, in any suitable manner to effect this interrelationship and assembly, and between the resultant juxtaposed vertical portions of these two clamping elements and with its ends seated in the trunnions or bearing recesses 29-29 and 30-30, is a pin or shaft 37 about which the two clamping levers 22 and 23 may pivot and which coacts also with the relative angularities of the juxtaposed parts 27-27 and 28-28 (see Fig. 5) to oppose downward disengaging movement of the two clamping levers 22 and 23 relative to the now strained split spring element 35 which acts upon them to strongly urge and hold the mating serrated jaw portions 31 of each in closing position.

As better appears in Fig. 5, the lever arms 20 and 21 by-pass the tube-like spring element 35, each to one side thereof and preferably with an appropriate extent of clearance. In the space between the arm 20 and the spring element 35 and curved (see Fig. 5) to substantially mate with the external curvature of the element 35 is a shank 39 of a spring clamping member generally indicated by the reference character 40 and shaped to provide a transversely elongated plate-like but curved clamping jaw 41. A similar and identically shaped spring clamping element 43 has a shank 44 extending into the space between the arm 21 and the other curved face of the spring element 35, being curved to be more or less conformed to the latter, and having a transversely elongated and curved clamping jaw 45. As seen in the side elevation, the general configuration of these two clamping elements 40 and 43 is substantially as shown in broken lines in Fig. 4, in which the member is shown in its position underlying the clamping lever element 22. With the shank parts 39 and 44 of the internal clamping elements 40 and 43 conforming externally to the curvature of the spring element 35 and with the top edges of their wider clamping jaw parts 41 and 45 underlying the opposed horizontal portions of the L-shaped extensions 27 and 28 of the clamping levers 22 and 23, the clamping elements 40 and 43 which are preferably made of a suitable spring sheet metal, are thus held in assembled relation to the other parts, aided by the reaction of the spring jaws 41 and 45 which, with the parts in the position shown in Fig. 5, are under strain. However and prefer-

ably the shanks 39 and 44 are joined together as indicated at 46, thus not only facilitating the making of the spring clamping elements 40 and 43 out of a single piece of sheet metal, as by stamping, but also permitting the joined or unitary shanks 39 and 44 to overlie the spring-mounting element 35 as shown in Fig. 5, so that when the assemblage is inserted into the interior of the housing 10 and the screws 33 put in place to secure the assemblage against the under side of the top wall 11, the band-like part that joins the shanks 39 and 44 is clamped between the spring element 35 and the top wall 11 and the two spring jaws 41 and 45 are thus dependably secured to resist downward stresses upon them as view in Fig. 5.

Upon completion of the fastening of the assemblage to the under side of the top wall 11, the upper ends of the lever arms 20 and 21 project upwardly beyond the upper face of the top wall 11 and to these projecting portions are secured two finger grips 48 and 49 which are preferably hollowed at their external side faces as indicated at 48^a and 49^a. The finger grips may be made of any suitable material such as molded resinous compounds and preferably are of substantial size to facilitate their manual manipulation. Due to the spring action of the spring part 35, the jaw plates 24-25 are tightly pressed against each other, thus holding the finger grips 48 and 49 apart and in maximum spaced relation. By gripping the finger grips 48 and 49 and pressing them toward each other, the holes 18 and 19 in the top wall 11 being of adequate width for this purpose, the jaw parts 24 and 25, which project materially below the lower edge of the housing 10, are separated as are also the spring jaw parts 41 and 45 whose lower edges fall just about in the plane of the lower edge or edges of the housing 10 and have curvatures (see Fig. 5) which, in relation to the curvatures of the end wall slots 16 and 17, form their width in end view or projection, a close approximation of a circle of a diameter preferably somewhat less than the thickness of the flexible cable with which these parts are to coact.

Accordingly by manipulating the finger grips 48-49 as above mentioned to open the clamping jaws 24 and 25 and thereupon bridging the cable, indicated at 50 in Figs. 7 and 8, across the under side of the housing 10 so that the cable enters the end wall slots 16 and 17, the cable thus also passes through the open jaws 24 and 25 and becomes engaged between and by the spring jaws 41 and 45. It enters between the latter if, as may be desired, the spring jaws are so tensioned initially that they are separated or opened appropriately at the same time that the rigid jaws 24 and 25 are opened, or they may be so tensioned as to require the application of a small force upon the cable to cam the cable into the grip of the spring jaws 44 and 45 for which purpose the lower end portions thereof may be reverse bends, as indicated in Fig. 5, to facilitate such entry of the cable.

If now the finger grips 48 and 49 are released, the entire device finds itself neatly attached to the cable 50 in the manner indicated in Fig. 7, the cable lying above the plane of the bottom edge of the housing, giving the appearance or illusion of a permanent or fixed attachment of the device to the cable. However, the spring grip of the jaws 41, 45, onto the flexible conductor cord or cable provides appropriate yielding action so that if desired, the device as a whole may be

pushed or slid lengthwise along the cable to position it at any desired point along its length. The attachment also is adequately secured and reliable to withstand normal or usual handling of the secured together cord and device as a unit.

As above indicated, the cable 50, usually in hospital signalling installations, is provided at its end with a signalling switch diagrammatically illustrated at 51 in Figs. 7 and 8, being usually of the push button self-locking type, as is well known. The above described attachment of the device to the cable permits flexibility of adjustment along the length of the cable in relation to the signalling switch 51 which it is desired to maintain within close reach of the patient and usually it is desired to secure it to the bed structure or to the bed-clothes such as a sheet, blanket or the like. Accordingly the finger grips 48 and 49 may now again be pressed together, thus opening the rigid jaws 24 and 25, but due to the spring action of the spring cable gripping jaws 41 and 45, the cable is not released; with the downwardly protruding rigid clamping jaws 24 and 25 thus separated or open, the sheet or blanket indicated at 52 in Fig. 7 or other part is brought into the open jaws 24 and 25 which tightly grip it upon release of the finger grips 48, 49. Frequently it will suffice if the device with the rigid jaws held open is simply pressed down upon or against a blanket, sheet, cover or the like so as to work a fold of the latter into the open jaws for gripping purposes. In any case the gripping action of the spring jaws 41, 45, on the cable is not interfered with in these processes of the application of the rigid jaws, for the spring jaws are substantially backed up by the cable held within their grip.

There are occasions when it may be desired to secure or suspend the signalling switch 51 by looping a portion of the cord 50 about a fixed part or structure such as the post or rail of the bed and in Fig. 8 such a fixed part is indicated at 53 with the cable looped thereabout as at 50a. Having so looped the cable, the two portions 50b and 50c are engaged by the clamping device, one cable part within the spring jaws 41, 45, and the other within the rigid jaws 24, 25. Or if the device is already attached in the above described manner to one cable portion such as the portion 50b, a succeeding manipulation of the finger grips 48, 49, and hence the external clamping jaws 24, 25, suffices to bring the other cable portion 50c into attachment by way of the jaws 24, 25.

Thus it is possible to avoid rapid deterioration as results from maltreatment of flexible cables or cords when the attempt is made to use them to tie the signalling switch at the desired location and also it is possible to avoid the damage caused by the use of pins or safety pins, and in any case a wide flexibility or range of adaptation to varied circumstances is provided, and it will be seen that these and other advantages are achieved in a simple, reliable and foolproof manner.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. A clamping device for clamping a cable and for clamping another part comprising a housing open at its bottom and having open ended slots

in two opposed depending walls to receive a reach of cable therein to thereby bridge the interior space in the housing, said housing having aperture means in the top wall, two clamping levers having means pivotally supporting them from the interior of the housing and for biasing them in opposite directions, said lever arms having portions extending upwardly through said aperture means to form finger pieces for manually actuating them from the exterior of said housing and having clamping portions extending downwardly beyond the plane of the bottom of the housing for clamping a part other than said bridging cable reach, and clamping means within the housing and actuatable by said two levers respectively and of an extent to engage and clamp substantially only said bridging cable reach.

2. A construction as claimed in claim 1 in which said clamping means for the bridging cable reach comprises two spring jaws which by their spring action are biased toward each other, and connections between said spring jaws and said two levers for effecting manual actuation thereof in response to actuation of said levers.

3. A construction as claimed in claim 1 in which said clamping means for the bridging cable reach comprises two spring-biased jaws respectively secured to said two lever arms and accommodated in the space between said lever clamping portions.

4. A construction as claimed in claim 1 in which said lever mounting and biasing means comprises a split tube-like spring element having means for securing it to a wall of the housing, said two levers having respective extensions entered into the split tube-like spring element and means spaced in a direction inwardly of said tube-like element for pivoting one extension against the other whereby the parts of said spring tube-like element bias said jaw portions of said levers toward each other.

5. A clamping device for clamping a cable and for clamping another part comprising two lever members each having a finger portion and a clamping jaw with means pivotally connecting them and biasing their jaws one toward the other, and spring biased clamping jaws of lesser reach than said first mentioned jaws with means mechanically assembling them to said levers for engaging a reach of cable that extends through the space within said first jaws whereby the latter are substantially unobstructed by said cable reach and can engage and clamp some other part to thereby fasten said cable reach.

6. A clamping device for clamping a cable and for clamping another part comprising two lever members having means pivotally connecting them and biasing them in opposite directions and each having a finger piece and a clamping jaw, said clamping jaws having a configuration to envelope therein a space of substantial dimension and length toward the ends of the jaws, and opposed spring clamping members within said clamping jaws and of shorter length than the latter for engaging a reach of cable and to hold it in a position where it does not obstruct said clamping jaws in engaging and clamping some other part for fastening said cable reach thereto.

7. A clamping device for clamping a cable and for clamping another part comprising two lever members having means pivotally connecting them and biasing them in opposite directions and each having a finger piece and a clamping jaw, said clamping jaws having a configuration to envelope

therein a space of substantial dimension and length toward the ends of the jaws, each of said lever members having secured thereto a spring clamping jaw that extends internally of its own clamping jaw and is of shorter length than the latter for engaging a reach of cable and holding it within said first clamping jaws in a position where the latter are sufficiently unobstructed to engage and clamp some other part to thereby fasten said cable reach.

8. A clamping device for clamping a cable and for clamping another part comprising two clamping jaw members having means mounting them for movement toward and away from each other together with means for biasing them toward each other to clamp a part engaged therebetween, finger piece members for actuating said jaw members in opposition to said biasing means, and supplementary clamping jaws having means mounting them within an inner portion of the space encompassed by said jaw members and shaped for gripping coaction with a cable said supplementary clamping jaws having means biasing them toward each other and having means interrelating them to said finger piece members to effect opening movement thereof in response to actuation of said finger piece members.

9. A clamping device for clamping a cable and for clamping another part comprising a housing open at its bottom and having open-ended slots

in two opposed depending walls to receive a reach of cable therein to thereby bridge the interior space in the housing, said housing having aperture means in the top wall, opposed clamping jaws depending from the interior of the housing and projecting through and beyond said open-bottom end of the housing and having means for biasing them in clamping direction for clamping a part positioned substantially underneath said housing, finger pieces exposed through said aperture means for manually actuating said clamping jaws, and spring-biased clamping jaw members within the housing and of a length in the direction toward said open bottom end to engage substantially only said bridging cable reach.

10. A construction as claimed in claim 9 in which said clamping jaw members have means mounting them between said opposed clamping jaws, said spring-biased jaw members having terminals forming substantially an outwardly divergent mouth for entering said cable reach therein against the spring-biasing action.

11. A construction as claimed in claim 9 in which said clamping jaw members have mechanical connections with said finger piece members to actuate them in opening direction in response to actuation of said finger piece members.
